UNITED STATES PATENT OFFICE

2,074,771

ROAD GUARD

Alan E. Brickman and George A. Gleason,
Worcester, Mass., assignors to The American
Steel and Wire Company of New Jersey, a cor-
poration of New Jersey

Application February 21, 1936, Serial No. 65,166

4 Claims. (Cl. 256—13.1)

This invention relates to road guards, one of the objects being to provide a safe but relatively inexpensive construction. Other objects may be inferred.

5 Referring to the accompanying drawings:

Figure 1 is an elevation of one example of the invention.

Figure 2 is a vertical section taken from the line II—II in Figure 1.

10 Figure 3 is a cross-section taken from the line III—III in Figure 2.

Figures 4 and 5 show details.

Figures 6, 7 and 8, are views similar to Figure 2 but showing possible modifications, these being 15 considered a second example of the invention.

Figures 9 and 10 show details of the second example.

Figures 11 and 12 are, respectively, plan and elevation showings of a third example of the invention.

Figures 13 and 14 show details of this third example.

In the first example of the invention the road guard means is formed by two wire ropes 1 which 25 are arranged in spaced parallel relationship. This relationship is maintained by brackets each formed by bending a length of bar to provide a body portion 2 and spaced legs 3 extending away therefrom, these brackets being arranged in each 30 instance so that the body portion 2 is offset from the ropes 1 away from traffic, the ends of the legs 3 being provided with suitable means for connecting them to the ropes 1.

If it is desired simply to maintain the spaced 35 relationship of the ropes 1 the above combination is all that is required. In case the bracket is to be used for mounting purposes, upstanding supports 4 and means for hinging the body portions of the brackets to these supports are provided. Such means may consist of the eye-bolts 5 illustrated by the drawings. The supports 4 are offset from the ropes away from traffic as are the body portions 2 of the brackets, this bringing the two together and permitting the described 40 hinging.

Various forms of means may be provided for connecting the ends of the legs 3 to the ropes 1. In the example being described the bars from which the brackets are constructed may be 45 formed to provide inwardly turned studs on the ends of the legs onto which nuts 6 may be screwed. This arrangement provides studs positioned in transverse association with the ropes and permits the use of U-clamps 7 which may be applied about the ropes and which are aper-

tured to fit over these studs. To provide for firmer clamping, fillers 8 are provided, these being apertured to fit over the studs within the clamps 7 and having ends 8a shaped to seat against the ropes 1. In the example under discussion two of these fillers are used between each of the clamps and their ends are beveled so that when the clamps are compressed by the nuts 6 these beveled edges function in the manner of clamping wedges.

In the case of the second example the same general construction is used excepting that the legs 3 of the various brackets do not turn inwardly but are simply apertured. Screws 6a are then threaded into the apertures in these ends so as to position the clamps 7. A further feature of this example is that the screws 6a may be inserted either upwardly or downwardly and thereby provide for different spacing of the ropes. The drawings illustrate the different possible positions. Furthermore, the clamps 7 may have their apertured parts placed on either side of the ends of the brackets and the screws 6a may be screwed completely through so that nuts 6b may be screwed on their projecting ends. This provides for a further possible variation in the spacing of the ropes.

This second example also illustrates the use of fillers that are different from those described in connection with the first example. These fillers 9 are much thicker than the fillers 8 and but one is used within each of the clamps. It is provided with an edge 9b that is curved to seat against the ropes. Although thicker than the fillers 8, these fillers 9 are not so thick but that they permit the screws 6a some latitude in their clamp-tightening action, whereby firm connections with the ropes are made.

The third and last example of the invention illustrates a construction wherein four of the ropes 1 are used. Furthermore, the brackets are associated in pairs, the brackets in each pair being arranged so that their body portions 2 are offset from the ropes away from traffic and are at different heights, the ends of the legs 3 of each of the brackets in each pair being connected with alternate ones of the ropes 1. Connectors 10 complete the installation by hinging the body portions of the brackets in each pair together.

This third example of the invention shows how it also may be adapted to mount the ropes 1 as well as to space them. An upstanding support 11 is offset from the ropes 1 away from traffic, and a pair of the brackets is mounted in the same arrangement described above excepting that the

body portions 2 of the brackets are hinged directly to the support 11 by suitable clamps 12. A further difference is to be seen in that the brackets are oppositely offset from the center line 5 of the support 11 while the ends of their legs 3 are connected to the ropes 1 in vertical alinement. This construction is particularly valuable in that it tends to eliminate the possibility of a colliding vehicle striking the ropes with such force as to 10 swing the brackets to permit the vehicle to strike one of the road guard supports.

We claim:

1. A road guard including the combination of a plurality of spaced strands providing a road 15 guarding means, brackets each providing a body portion and spaced legs extending away therefrom, and means for connecting the ends of said legs with said strands, said brackets being arranged with their body portions offset from said 20 strands away from traffic and at different heights, the ends of the legs of each of said brackets being connected with alternate ones of said strands and their respective body portions being hinged together.
- 25 2. A road guard including the combination of a plurality of spaced strands providing a road guarding means, brackets each providing a body portion and spaced legs extending away therefrom, means for connecting the ends of said legs 30 with said strands, said brackets being arranged with their body portions offset from said strands away from traffic and at different heights, the

ends of the legs of each of said brackets being connected with alternate ones of said strands, an upstanding support and means for hinging the respective body portions of said brackets to said support.

5

3. In a road guard including the combination of spaced strands providing a road guarding means, a bracket providing a body portion and legs extending away therefrom, said legs carrying studs positioned for transverse association 10 with said strands, U-clamps for application about said strands and which are apertured to fit over said studs, fillers that are apertured to fit over said studs within said clamps and which have ends shaped to fit against said strands, and means 15 for fastening said U-clamps to said studs.

4. In a road guard including the combination of spaced strands providing a road guarding means, a bracket providing a body portion and legs extending away therefrom, said legs carrying studs positioned for transverse association 20 with said strands, U-clamps for application about said strands and which are apertured to fit over said studs, fillers that are apertured to fit over said studs within said clamps and which have 25 ends shaped to fit against said strands, and means for fastening said U-clamps to said studs, said legs adjustably carrying said studs so they may be arranged to extend either upwardly or downwardly therefrom.
